UNITED STATES PATENT OFFICE.

WINFIELD S. HUSTON, OF FAYETTE COUNTY, OHIO.

FLOOD-GATE.

SPECIFICATION forming part of Letters Patent No. 380,653, dated April 3, 1888.

Application filed January 7, 1888. Serial No. 260,067. (No model.)

To all whom it may concern:

Be it known that I, WINFIELD S. HUSTON, a citizen of the United States, residing in the county of Fayette, and State of Ohio, have invented certain new and useful Improvements in Flood-Gates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in flood-gates of that class which are pivotally suspended from a beam across a stream, and which are adapted to be swung upward by the force of the water.

My invention consists in a locking device which is automatically released as the gate is swung upward, there being also a counter-weight which operates upon the releasing of the locking device, the gate being thereby pulled up out of the way of the water.

Figure 1 is an elevation of my improved flood-gate, as seen from the lower side. Fig. 2 is an end elevation of the same, the gate being partially elevated. Fig. 3 is a cross-section through line $x x$, Fig. 1. The gate in this figure is shown elevated to its extreme height.

At ordinary stages of water in the stream over which the flood-gate is suspended it is allowed to swing outward from a perpendicular to a certain limit, its weight being borne up only by the force of the water against it; but as soon as the water rises above a certain height the locking device is released, freeing a counter-weight which is suspended by a chain passing over a pulley above the gate, and connected with the latter, and this counter-weight, thus released, serves to pull the gate up to a horizontal plane above the water-way.

In the drawings, A is the gate, which consists of the two end pieces or hangers, c, of square lumber of the necessary length. These hangers are connected by the longitudinal beam d, the ends of which are tenoned in the hangers near the middle of the latter. The apron e is made of heavy plank, extending from one hanger to the other and up onto the beam d, and is fastened upon the upper side or face of the gate.

The gate A is suspended by strap-irons b b (secured by bolts and nuts to the hangers c c) from the eyebolts a a, which latter are secured in the truss-beam B, extending over the gate across the stream. The beam B is rigidly fastened at the ends into posts C C, which latter stand on opposite sides of the stream over which the gate is suspended. To give firmness to the gate care should be taken to set the posts deep into the ground, or secure them by mortise and tenon into heavy timbers sunk in the ground, so as to preserve their alignment, also that the gate may be at all times in line therewith and perpendicular to the stream when it hangs down. The beam B is best secured in the posts C C by mortise and tenon, as shown. The eyebolts a a are inserted through the beam B, nearest the front side of the latter, and the strap-irons b are secured to the upstream side of the hangers c c, so that when the gate is thrown up to a horizontal plane (as seen in the vertical section, Fig. 3) the top ends of the hangers strike the beam B, preventing the gate from being raised any higher, the length of the strap-irons above the hangers being just sufficient to allow of this. The ends of the strap-irons have eyes or curved hooks on them to engage the eyebolts a a. The hangers c c are tapered slightly from the beam d to their lower ends to reduce their weight.

On the beam B, at the middle, is an upright post, f, having a cleft mortised out of its top end, in which is a fixed pulley-wheel, g, at right angles with the line of the beam and gate. Under the post f, and extending outward from the lower side of the beam B, is a short piece, h, having a notch of V shape in its outer end. This piece h may be of oblong shape, having its front end formed into a tenon, and extend through the lower end of post f, which latter is preferably formed into a long tenon and extends down through a vertical mortise in the beam B far enough below the beam to allow the tenon end of h to pass through it, as described. A hole is bored in the tenon of f, below h, and a wooden pin, driven through this hole, secures both the post F and arm h in their places.

By reference to the figures it will be noticed that the apron e is on the front side of the gate and projects above beam d along its whole extent. At the middle line of the gate

a chain, *l*, is fastened by one end near the lower edge of the apron and extends from the lower side up over the pulley *g*, and has a weight, *m*, on its opposite end, which hangs on the upper side of the gate. On this chain (near the middle) is a ball, *n*, rigidly secured thereto. To bring the gate to its normal position, as seen in Fig. 1, the chain *l* is drawn down over pulley *g*, raising the weight *m* until the ball *n* is below the piece *h*, (the chain being pulled outward from its engagement with notch *i* to let the ball pass, when it is dropped back into the notch with the ball *n* below the latter.) The weight *m*, which is drawn up near the beam, holds the ball in engagement with the notch *i*, and that part of the chain below ball *n* being slack allows the gate to swing freely downward (or down stream) to a certain limit. Under the chain, on the middle line of the gate, is an inclined board, *k*, which extends from near the lower edge of the apron *e* (on the downstream side of the latter) up above the rail *d* nearly to the end of the piece *h*. It is high enough to just clear the outer end of the notched piece *h* as the gate swings upward. This board *k* is provided at the upper end with a curved notch, *j*, which latter is made semi-circular to allow the chain to pass through it freely, while at the same time it is small enough to catch against the ball *n* as it slides upward on the chain. The tripper *k* is secured to the apron below and to the beam or rail *d* by bolts. As the gate rises from the force of the water, the upper end of tripper *k* comes in contact with ball *n*, and, pushing it outward, releases it from the notch *i*, when the weight

m falls and pulls the gate upward until it is arrested by the upper ends of its hangers *c c* striking the lower side of the beam *B*, where to it is held by the weight above the stream.

I claim as my invention—

1. The combination, with a flood-gate suspended from a beam, as described, of a chain, a weight attached thereto, a ball on said chain, a pulley above the suspending beam over which said chain is carried, the notched piece with which said ball engages, and the tripper adapted to engage said chain below said ball and to disengage the latter as the gate reaches a limited height, and thus free the weight and cause it to raise the gate to its full height, substantially as set forth. 45

2. The combination, with a flood-gate, of a fixed pulley, a chain having one end attached to said gate and passing over said pulley, a weight at the opposite end of said chain adapted to elevate said gate, a ball on said chain between the weight and the end attached to the gate, a device to hold said ball in engagement when said weight is drawn up, and thereby prevent the latter from operating the gate with said ball engaged, and a tripping or detaching device to disengage said ball and allow said weight to elevate the gate when the latter shall have reached a limited height by the force of the water, substantially as hereinbefore set forth. 55

In testimony whereof I affix my signature in presence of two witnesses.

WINFIELD S. HUSTON.

Witnesses:

POPE GREGG,
JAMES STRALEY.
